PROCESS OF REPRODUCING SURFACE APPEARANCE OF NATURAL OBJECTS

Application filed March 21, 1928. Serial No. 263,439.

This invention is concerned with improvements in the art of reproducing the surface appearances of natural objects such as marble slabs, etc. In my prior disclosure of a 5 marbleizing process as set forth in my application, Serial Number 163,200 filed January 24, 1927, which has become Patent No. 1,682,067, dated August 28, 1928, I disclosed a method of using an etched plate for reproducing in natural colors a marble appearance 10 on surfaces of materials other than marble, and wherein I proposed the use of a negative plate which, when used to form a transfer, would cause the reproduction or formation 15 of the veins or cleavage lines of the marble to be defined by ink omissions in the transfer, and I utilized such a plate by first applying to the surface of the material being treated a ground coat which would be of a 20 color simulating one of the natural colors of the marble. I then placed over the ground coat pigment, after the ground coat had dried, a transfer taken from the plate on one 25 color and then I subsequently applied over that transfer a second transfer of a different color darker in shade than the previous color, and the second transfer was applied so that the cleavage lines or veins of the marble of the second transfer would be out of register 30 with the veins or cleavage lines of the previous transfer, thus producing a highly pleasing reproduction of the marble surface being imitated. No two pieces or articles thus finished would be exact duplicates in surface 35 appearance. However, in my process referred to, the major color of the marble surface was obtained by a pre-determination of the two colors of the transfers which when blended by and superposed upon the ground 40 coat would approximate the desired composite color result.

However, in obtaining the final major or dominating color of surface appearance by compositing the transfer colors, I found that 45 the cleavage or vein colors in some instances, while satisfactory, were not as near to the original natural colors as might be obtained by a modification of the process.

My present invention, therefore, is concerned with a method of reproducing a mar-

ble surface to obtain the general pleasing results obtained by my prior process but wherewith I may obtain a more accurate reproduction of the colors of the marble cleavages or veins while at the same time obtaining a proper reproduction or matching of the dominating major color of the marble surface being reproduced.

Other objects of my invention will herein-after become apparent from the following 55 description of apparatus which is found to be satisfactory in carrying out the steps of my present novel process. The essential characteristics thereof are summarized in the claims.

In the drawings, in Fig. 1 I show in conventional manner and more or less diagrammatically a marble surface to be reproduced. In Fig. 2 I show an etched surface hereafter referred to as a negative printing surface 60 for reproducing only certain of the colors present in the veins or cleavage lines of the natural surface of the marble being reproduced; Fig. 3 is a positive printing surface 65 utilized for reproduction of the dominating major color of the natural marble and for also reproducing certain of the cleavage lines and formations of the marble surface; and Fig. 4 is a diagrammatic representation 70 of the composite of the various colors applied to the surface being treated to effect 75 simulation of the natural surface shown in Fig. 1.

Throughout the specification in referring 80 to "positive" and "negative" printing surfaces I use the words "positive" and "negative" in the same sense as they are used in photography. Thus in a reproduction made from a positive printing plate the dark portion of the object reproduced will be indicated by pigment, while in a reproduction made from a negative printing plate the dark portion of the object reproduced will be indicated by omission of pigment.

For purposes of illustration I will describe my process as it is employed in the reproduction of surfaces in which the general tonal effect is dark, and the definite colour lines are lighter than the background. However, it is to be understood that my process may

be used equally well to reproduce surfaces having light backgrounds and dark contrasting portions.

In carrying out the steps of my process for artificially forming a surface in imitation or simulation of the natural appearance of another vari-colored surface such as the surface of a marble slab, etc., I first select a suitable pigment which may be utilizable as a ground coat on the surface to be treated. The physical characteristics of this ground coat may vary in accordance with the nature of the physical characteristics of the material being treated. For example, some materials, such as steel, have surfaces relatively non-porous as compared with materials such as plaster-board, pulp-board, asbestos-board, etc. but regardless of the filler requirements of the ground coat, I maintain a color characteristic which will correspond to one of the dominating colors present in the natural surface, as for example, the varying color tones in the vein or cleavage formations in a natural marble slab.

I next prepare a photographic negative of the natural surface and then produce from this negative by the use of a carbon resist an etched negative printing plate or roll which printing plate or roll will form only the definite color lines such as the marble veins or cleavage formations, and this etched plate may be either a half tone or photo-gravure plate, and the transfer may be effected from such etched plate, the surface being treated by the use of a resilient roll in the well-known manner.

I then prepare a second etched plate or roll which is the reverse of the first plate or roll and in the form of a positive. The plate may be derived by using a photographic positive of the natural surface to form a negative carbon resist, and forming a positive printing surface by etching the plate or roll through the negative carbon resist. In this plate, when marble having a dark background and lighter cleavage lines is the object, the veins or cleavage line formations are indicated in the transfer taken therefrom by ink or pigment omission that is, the major portion of this printing plate is ink or pigment in the transfer result, and I apply a pigment thereto, which corresponds to the final major dominating color appearance of the original natural marble slab, the color, however, being slightly modified when blending with the ground coat.

I then apply this second transfer over the previous transfer but out of register therewith and thus obtain, in so far as cleavage line formation and vein formations of the marble are concerned, a blending of three colors, namely, the color of the ground coat, the color of the first transfer and the color of the final dominating colored transfer. It will thus be seen that I obtain in some in-

stances exposure of the original ground coat color; in other places the original color of the first transfer; a blending of the last color into the ground coat color, a blending of the ground coat with the first color, and in other instances, a blending of all three colors, thus giving an effect very closely approximating, in the instant case, the natural appearance of a marble slab.

In making a reproduction of a marble surface which is generally light and which has cleavage lines darker than the background I prefer to reverse the order of applying the transfer. That is, I first apply a transfer from the positive plate, and then apply a transfer from the negative plate over this, as it is advantageous to make the first transfer from the plate in which the cleavage lines are indicated by pigment.

Referring now to the drawings, Fig. 1 is a diagrammatic representation of a marble slab surface having three colors and variably blending at different portions of the surfaces. The major color indicated by the line field 10 being the last color applied and with the use of the printing surface shown in Fig. 3; the line fields 12 being produced by the negative printing surface shown in Fig. 2. The printing surfaces in Figs. 2 and 3, in so far as zones or outlines are concerned, being inverted relative to the corresponding zones shown in Fig. 1. In Fig. 4 the reproduced surface is shown and is produced by applying first a ground coat of the selected color, then applying a transfer taken from the surface Fig. 2, and thereafter a second transfer is taken from the surface shown in Fig. 3 and applied over the first transfer, whereby certain zones 15 will be present which comprise tonal blending of the ground color and the first transfer, and other zones 16 will comprise blending of the colors of the first and second transfer. These blending of tones will vary in tonal depth depending upon the etched printing surfaces shown in Figs. 2 and 3. An unending number of variations will be obtained in the color combinations by inverting the transfer rolls after the transfers have been taken from Figs. 2 and 3, or direct transfers may be made or either one or the other inverted in accordance with the results desired.

While the surface shown in Fig. 4 will not be an exact reproduction of the surface shown in Fig. 1, the imitation or simulation of the natural surfaces, shown in Fig. 1, will be quite striking.

One of the advantages in the use of reproducing marble surfaces in this particular manner is to be found in the fact that only a very small amount of pigment is used in forming the first transfer, thus permitting of its rapid drying and accordingly, accelerating of the production of the surfaces of the primary desired colors in order to obtain the

final dominating major color effect of the natural marble slab, and a more accurate approximation of the natural colors is possible due to the confining of the pigment of the first transfer to only a minor part of the total surface being treated. It will be apparent, however, that the negative transfer could be first applied and then the position superposed thereover, but the tonal results would not be quite as satisfactory as the obtainable result described.

I claim:

1. The process of reproducing a marble appearance on a hard surface, comprising using two etched printing surfaces, one prepared from a positive carbon resist and the other prepared from a negative carbon resist of a marble surface to be simulated, by first applying a ground coat to the surface to be finished, and then using one of the etched plates or rolls to make a transfer of the marble vein or cleavage lines in a color different than the color of the ground coat, then using the other plate or roll in the application of a different colored transfer which is superposed over the previous transfer but out of register therewith.

2. The process of reproducing a marble appearance on a hard surface, comprising using two etched printing surfaces, one prepared from a positive carbon resist and the other prepared from a negative carbon resist of the marble surface to be simulated by first applying a ground coat to the surface to be finished, and then using the positive etched plate or roll to make a transfer of the marble vein or cleavage lines in a color different than the color of the ground coat, then using the negative plate in the application of a different colored transfer which is superposed over the previous transfer but out of register therewith and thus reproduce certain of the vein or cleavage line formations on the original marble surface by pigment or ink omission during the act of the second transfer whereby part of the previous transfer and also the ground coat will be exposed through such vein or cleavage line link omission.

3. The process of reproducing a marble appearance on a hard surface, comprising using two dissimilar etched printing surfaces, prepared by photographing marble surfaces to be simulated, by first applying a ground coat to the surface to be finished, and then using one etched printing surface to make a transfer of marble veins or cleavage lines in a color different than the color of the ground coat, then using the second printing surface in the application of a second but darker toned transfer which is superposed over the previous transfer but out of register therewith and thus reproducing certain of the vein or cleavage line formations of the original marble surfaces by the resulting blending of the full,

half and quarter tone effects of the ground coat color and first and second transfer colors.

4. The process of reproducing a marble appearance on a hard surface comprising using two dissimilar printing surfaces derived by the photographic method of printing surface reproduction of marble surfaces to be simulated by first applying a ground coating of pigment to the surface to be finished, then using one of said printing surfaces to make a transfer of marble veins or cleavage lines in a color different than the color of the ground coat, then using the second printing surface in the application of a second transfer which is superposed over the previous transfer but out of register therewith, and thus reproducing certain of the vein or cleavage line formations of the original marble surfaces by the resulting blending of the full tone, half tone and quarter tone effects of the first and second transfer colors in contrast upon the ground coat color.

5. A process for simulating the natural appearances of surfaces on the surfaces of dissimilar materials comprising using two etched printing surfaces, the one being derived by using a photographic negative of the natural surface to form a positive carbon resist and then etching the printing surface through the positive carbon resist, thereby obtaining a negative printing surface; the other being derived by using a photographic positive of the natural surface to form a negative carbon resist and then etching the printing surface through the negative carbon resist thereby obtaining a positive printing surface, by making alternate transfers of pigment from the said printing surfaces to the surface being finished, the said transfers being out of register with each other.

6. A process for simulating marble surfaces on the surfaces of materials other than marble, which includes the steps of making alternate transfers from positive and negative graining plates or rolls to the surface being finished, in the sequence of colored transfer or impression desired but with the subsequent transfers out of register with the previous transfers.

In testimony whereof, I hereunto affix my signature.
